ARTICLE OF MANUFACTURE

Filed July 26, 1926

INVENTOR.
FRANK W. EPPERSON
BY Joseph B. Gardner
his ATTORNEY.

UNITED STATES PATENT OFFICE.

FRANK W. EPPERSON, OF OAKLAND, CALIFORNIA.

ARTICLE OF MANUFACTURE.

Application filed July 26, 1926. Serial No. 124,841.

My invention relates to an original package for a beverage-base in dry form, and particularly to a package which is arranged to provide for the serving of the beverage 5 therefrom in liquid form.

An object of the invention is to provide a package of the character described which provides a serving cup of such capacity with respect to the beverage base contained there- 10 in that hydration of the base to fill the cup will produce a beverage of predeter- mined strength.

Another object of the invention is to provide a package of the character described 15 which is so shaped and sealed as to prevent contamination of the contents and cup surface during the transportation thereof, whereby it is particularly sanitary.

A further object of the invention is to 20 provide a package of the character described which is of minimum weight and is lacking in fragility.

A still further object of the invention is to provide a package of the character de- 25 scribed which is of simple structure, and may be manufactured so inexpensively that the container portion may be discarded after the removal of the beverage therefrom.

Yet another object of the invention is to 30 provide a package of the character described in which a closure member therefor is arranged to be used as a stirrer for the beverage.

And still another object of the invention 35 is to provide packages which are nestable so that a plurality thereof may be packed to occupy a minimum of space.

The invention possesses other objects and 40 features of advantage, some of which, with the foregoing, will be set forth in the following description of the preferred form of my invention which is illustrated in the drawings accompanying and forming part 45 of the specification. It is to be understood, however, that I do not limit myself to the showing made by the said drawings and description, as I may adopt variations of the preferred form within the scope of my invention as set forth in the claims.

50 Referring to said drawings,

Figure 1 is a perspective view of a section of one embodiment of the package of my invention.

Figures 2 and 3 are perspective views of

closure members forming part of the pack- 55 age.

Figure 4 is a side view showing a plu- rality of the packages in nested relation.

Beverages in liquid form are compara- 60 tively bulky so that whether they are to be stored, displayed on a shelf, or transported, they occupy an undue amount of space. Furthermore, the containers therefor must usually be made of glass, which containers are both heavy and relatively expensive and 65 are subject to breakage. Then again, the usual beverage containers are not arranged for the direct drinking of the contents there- 70 from, so that a drinking vessel must be supplied for serving them. Since the prin- 75 cipal ingredient of most beverages from a quantitative standpoint is water, the use of concentrated liquid or dry bases which are arranged to be hydrated to produce bever- 80 ages has been resorted to, but such bases 75 have heretofore been so put up for vending that their use has frequently proved un- sanitary and inconvenient. In accordance 85 with my invention, however, I provide a package for a dry beverage base which is so 80 constituted that it provides a drinking ves- 90 sel for the beverage produced by hydrating the base therein and also provides a stirrer, it being noted that each package is pref- 95 erably arranged to contain only enough base 85 to provide a normal amount of beverage for one drink. Since the capacity of the pack- 90 age for the hydrated beverage must exceed its required capacity for the dry base, the packages are preferably arranged to be 95 nested together, so that a number of pack- ages will together occupy a minimum of space. And, furthermore, each package is so arranged that the charge of beverage base 95 therein is protected against the penetration of dust or other contaminating matter before the package is opened.

As herewith particularly illustrated, the 100 article of my invention comprises a cup 6 adapted to retain liquid in the cavity thereof and containing a charge 7 of a beverage 105 base, such charge being preferably in dry form and sealed within the cup cavity ad- jacent the bottom thereof. The charge 7, it will be noted, preferably comprises a com- 105 plete base for the beverage, so that the mere addition of water thereto to fill the cup cavity will produce a beverage of predeter-

mined strength. The cup 6 may be of any suitable form, but for certain reasons to be hereinafter specified, I prefer that it be generally frustro-conical in outline, with the opening thereof at the larger end.

Means are provided whereby the charge 7 is arranged to be normally held sealed in fixed position in the cup. As here shown, such means comprises the use of a closure 10 member 8 having a disc shaped portion 9 which is arranged to have the lower surface thereof engage the top of the charge while its periphery lies adjacent the cup wall 11. To facilitate the removal of the member 8, 15 the latter is preferably provided at one edge portion with an extension or tab 12, which extension is arranged to lie along the wall when the member 8 is operatively disposed in the cup. The extension 12 preferably extends 20 at least to the cup lip 13, so that it may be readily grasped for effecting its removal without touching the inner walls of the cup. Means are provided for sealing the member 8 in its position, and as here shown, such means comprises the provision 25 of a wrapping member 14 preferably completely overlying and enclosing the outer wall surfaces and the inner wall surface portions lying outwardly of the member 8, 30 the edges of such wrapper preferably being disposed against the outer side 16 of the closure member. The wrapper 14, it will be noted, is preferably formed of a flexible and impervious material such as oiled paper 35 so that the cup may be thereby maintained in sanitary condition during the storage and transportation thereof. Sealing of the package may be effected in any desired manner, and as here shown, such sealing is effected 40 by means of a second disc shape member 17 which is arranged to closely fit the cup adjacent and above the closure member 8 whereby the wrapper 14 may be held tightly engaged with the cup wall 11 and the wrapper ends 45 be held against the closure member side 16. The member 17, it will be noted, is provided with a tab 18 for assisting the removal thereof, such tab being here shown provided at an edge of the member and disposed 50 opposite the tab 12 of the inner closure member whereby the comparatively straight chord forming part of its perimeter at its juncture with the member will, by allowing space for the tab 12, between it and the cup 55 wall prevent radial distortion of the cup as the member 17 is pressed into place. It will now of course be evident that the conical slope of the cup walls is particularly useful in permitting the wedging of the 60 closure members into their places.

The member 8, it will now be noted, is preferably longitudinally scored, while the portion 9 of such member is diametrically scored along a line meeting the scoring of 65 the portion 12, so that when the member 8 is

removed from the cup and the portions 9 and 12 thereof disposed in substantially coplanar relation, the member may be creased along the score line thereof to provide a relatively stiff stirrer which may be 70 used in facilitating the solution and mixing of the base in the water.

It will, of course, now be clear that to prepare the article of my invention, the base is first placed in the cup, the primary closure 75 member 8 is positioned thereover, the wrapper 14 is then applied as indicated, and the completion of the package is then effected by pressing the closure member 17 into its place. To prepare the beverage for consumption, the member 17 would first be removed, followed by the wrapper and member 8, after which water would be added to substantially fill the cup and the base stirred into the water by means of the member 8 80 disposed for use as a stirrer as previously described.

Owing to the fact that a considerable portion of the cup space is not utilized in the assembled package, the different packages 90 may, on account of the particular shape of the cups, be nested, as illustrated in Figure 4, to thereby occupy a minimum space. It will now be noted that the slope of the cup walls is preferably such that the diameter 95 of the closure members 17 substantially equals that of the cup base, so that the cups, when nested, will cooperate to produce a particularly indestructible assembly and so may be transported without damage. It 100 will be noted that the cup and closure members may be conveniently constructed of cardboard or other inexpensive material, so that they may be discarded after the consumption of the beverage.

I claim:

1. A package of the character described comprising a drinking cup, a charge of a beverage base disposed in the cup cavity and arranged to be hydrated therein to provide a beverage to be drunk therefrom, and removable means arranged to secure and plurally seal said charge in said cup cavity.

2. A package of the character described comprising a drinking cup, a charge of a 110 beverage base disposed in the bottom portion of the cup cavity, and a closure member for said cavity portion removably disposed in said cup and arranged to be utilized in its entirety to provide a stirrer for a 115 liquid in said drinking cup.

3. A package of the character described comprising a drinking cup, a charge of a beverage base disposed in the bottom portion of the cup cavity, a closure member for 125 said cavity portion arranged to be operatively disposed at the open side thereof, means on said member arranged to facilitate the removal thereof from its closure relation to said cavity, and a covering en- 130

veloping the inside and outside exposed surface of the cup.

15

4. A package of the character described comprising a drinking cup, a charge of a beverage base disposed in the bottom portion of the cavity of said cup, a removable closure member for said cavity portion, an envelope enclosing said cup and charge and having the opening edges thereof disposed over said member, and a sealing member arranged to be removably disposed over said envelope edges and arranged to effect the forcible engagement of said en-

velope with the inner surface of said cup around its perimeter.

5. A package of the character described comprising a cup-like container, a charge of a beverage base disposed in the container cavity, and removable means arranged to secure and seal said charge in said cavity 20 with a plurality of air-tight joints.

In testimony whereof I have hereunto set my hand at Oakland, California; this 19th day of July, 1926.

FRANK W. EPPERSON.
